CARRIER ASSEMBLY FOR RAILWAY COUPLERS

Loree Elwyn Furniss, Groveport, Ohio, assignor to The Buckeye Steel Castings Company, Columbus, Ohio

Application February 24, 1955, Serial No. 490,236

7 Claims. (Cl. 213—61)

The present invention pertains to a railway coupler support and more particularly relates to improvements in the structure and the mounting of the carrier member on the striker so that the carrier may move laterally during horizontal angling movements of the coupler stem without subjecting the springs supporting the coupler to shearing action.

An object of the invention is to provide a support for a railway coupler wherein the carrier member may move laterally relative to the striker without shifting the upper ends of the springs which support the carrier member to thereby avoid the development of shearing stresses in the supporting springs and to provide an assembly which serves to return and maintain the carrier member in a central position relative to the front opening in the striker.

A more detailed object of the invention pertains to the provision of rollers between the carrier member and a spring abutment member carried by the upper ends of the supporting springs whereby the carrier member rides on such rollers during lateral movements with respect to the striker and to provide surfaces cooperating with the rollers which tend to return the carrier member to a neutral position.

A further object of the invention is to support a coupler carrier member for rolling horizontal movements on a member carried by upper ends of a plurality of springs and to provide means for guiding the upper ends of the springs for vertical movements to prevent lateral movements of upper portions of the springs during horizontal movements of the carrier member with respect to the striker.

Other objects and features of the invention will be appreciated and become apparent to those skilled in the art as the present disclosure proceeds and upon consideration of the accompanying drawings and the following detailed description wherein an embodiment of the invention is disclosed.

In the drawings:

Fig. 1 is a front elevational view of a lower portion of a striker with a coupler carrier assembly embodying the invention in place while the portion shown at the right is a sectional view taken on the line 1—1 of Fig. 2.

Fig. 2 is a sectional view of the striker and the carrier assembly taken on the line 2—2 of Fig. 1.

Fig. 3 in the left portion is a sectional view of a forward portion of the striker taken on the line 3—3 of Fig. 4 while the right portion is a plan view.

Fig. 4 is a sectional view of the trough structure carried by the striker taken on the line 4—4 of Fig. 3.

Fig. 5 is a fragmentary front elevational view of a portion of the striker.

Fig. 6 is a sectional view of a detail taken on the line 6—6 of Fig. 1.

Fig. 7 is a plan view of the carrier member.

Fig. 8 is a front elevational view of the carrier member with the right hand portion showing a section taken on the line 8—8 of Fig. 7.

2

Fig. 9 is a transverse sectional view of the carrier member taken on the line 9—9 of Fig. 8.

Fig. 10 is a front elevational view of a spring abutment member.

Fig. 11 is an inverted plan view of the spring abutment member and Fig. 12 is an end view.

Fig. 13 is an exploded perspective view of one of the rollers for restraining upward movement of the carrier member.

Fig. 14 is a side elevational view of one of the carrier supporting rollers and Fig. 15 is an end view.

The striker for a draft rigging is shown at 16 provided with a front opening 17 in which the stem 18 of a coupler is accommodated. The front opening 17 is of a larger horizontal dimension than a corresponding spacing of the outer surfaces of the coupler stem so that the draw bar may move laterally during horizontal angling of the coupler. The stem 18 of the coupler rests on and is supported by a carrier member 19. The carrier member is resiliently supported by means of springs as hereinafter described and the member 19 is moved laterally with the coupler stem.

A trough structure is provided at the front and lower portion of the striker 16 and includes a front wall 21 and a rear wall 22. The lower central portion of the trough structure is closed by means of a bottom wall 23 while the side portions of the trough structure are open as shown at 24. A plurality of spring positioning lugs 26 project upwardly from the bottom wall 23. The front wall 21 is provided with a plurality of relatively large weight reducing openings 26 and openings 27 and 28 may be provided in the lower central portions of the front and rear walls to permit the escape of cinders and the like. Additional openings 29 are provided in the bottom wall 23 for similar purposes.

The front wall 21 of the trough structure is provided with two horizontally elongated openings 31 and 32 as shown in Figs. 1 and 5. These openings have horizontally disposed top edges. The lower boundary edges of the openings 31 and 32 are of concave shape. The front wall 21 of the trough structure in the areas bounding the openings 31 and 32 is reinforced by means of ribbing 33. This ribbing is arranged around these elongated openings and merges with a rib 34 which extends horizontally along the forward top edge of the trough structure.

The rear wall 22 of the trough structure is provided with similar elongated openings 36 and 37 as shown in Figs. 6 and 1. These openings have horizontally disposed upper edges and concave lower edges corresponding to the shape of the elongated openings 31 and 32 in the front wall 21. The openings 31 and 36 are in horizontal alignment while the openings 32 and 37 are in the same horizontal plane. The top edge portion of the rear wall 22 is reinforced by means of a rib 39. The side walls of the striker are provided with open areas 41 one of which is shown in Figs. 2 and 4 to accommodate the rear end portions of means hereinafter described for restraining upward movement of the carrier member 19.

The structural characteristics of the carrier member 19 will be more clearly appreciated upon consideration of Figs. 7 to 9. This member includes a top plate 42 which has a flat upper surface on which the coupler stem 18 is adapted to rest. A lug 43 extends upwardly from each end of the top plate 42. These lugs are arranged at opposite sides of the coupler stem 18 so that the carrier member is moved laterally during horizontal angling of the coupler shank.

A flange 44 depends from the plate 42 at the rear edge thereof and extends throughout the length of the plate 42. The lower edge 46 slopes upwardly in proceeding

towards the front of the carrier member 19. This sloping edge 46 is adapted to contact the top edge of the rear wall 22 of the trough structure during extreme downward swinging movements of the coupler stem. A sloping face 47 provides the under surface of the top plate 42 along the front thereof which engages the top edge of the front wall 21 during maximum downward movement of the carrier member. The top surface of the plate 42 remains in flat engagement with the under surface of the coupler stem 18 when both the front and rear portions of the carrier member engage the top edges of the trough structure.

A loop 48 is provided at one end of the carrier member 19 and a similar loop 49 is carried by the opposite end. The upper portion of the loop 48 is formed integral with the associated lug 43 and the lower portion is connected to the plate 42 by an upwardly extending arm 59. The loop 49 is formed integral with the other lug 43 and is similarly connected to the top plate 42. The loops 48 and 49 are constructed like those disclosed in my application Serial No. 389,655, filed November 2, 1953. The loop 48 is provided with an upwardly facing concave surface 61 while the loop 49 is provided with a similar upwardly facing concave surface 62. The under surface of the plate 42 of the carrier member is provided with two downwardly facing concave surfaces 63 and 64 and the utility of these arcuate surfaces will become apparent as the present disclosure proceeds.

A plurality of springs 66 are provided within the trough structure for resiliently supporting the carrier member. The lower ends of these springs engage the bottom wall 23 and are maintained in spaced positions thereon by the lugs 26. A spring abutment member 67 is arranged over the upper ends of the springs 66. This member includes a plate portion having a relatively flat under surface 68 as shown in Fig. 11 which is adapted to be engaged by the upper ends of the springs 66. A plurality of spring positioning lugs 69 depend from the plate portion of the abutment member for maintaining the upper ends of the spring 66 in spaced relation. The plate portion of the spring abutment member 67 is provided with two upwardly facing concave surfaces 71 and 72 which are generated about horizontal axes and each has a radius similar to that of the downwardly facing concave surfaces 63 and 64 on the carrier member 19.

Two ears 73 and 74 depend from the plate portion of the spring abutment member 67 at the front thereof. These ears are so shaped and positioned as to provide a space or slot 76 therebetween. These ears 73 and 74 are arranged on the opposite sides of a vertically disposed rib 77 which extends vertically along the central inner surface of the front wall 21 of the trough structure. A lug 79 depends from the central rear portion of the spring abutment member 67. This lug is adapted to fit within a vertically disposed groove 81 in the rear wall 22 of the trough structure.

The abutment member 67 is supported by the upper ends of the springs 66 and a pair of rollers 82 of the type shown in Figs. 14 and 15 support the carrier member 19 on the spring abutment member 67 as shown in Figs. 1 and 2. One roller 82 is arranged between the concave surface 63 on the carrier member 19 and the concave surface 71 on the spring abutment member 67 while the other roller 82 is accommodated between the concave surface 64 of the carrier member and the concave surface 72 of the spring abutment member. The carrier member is thereby supported for lateral movements relative to the striker 16 by the rollers 82. The rollers 82 are prevented from escaping endwise from operative positions by means of depending flanges 83 on the carrier member 19 (Figs. 1 and 8) and the flange 44.

The draw bar of the coupler which rests on the carrier member 19 is resiliently supported by the springs 66. The load imposed on the carrier member 19 is transmitted through the rollers 82 onto the spring abutment member

67 which is supported by the upper ends of the helical springs 66. Upward movement of the carrier member 19 is limited by a pair of rollers 88 having enlarged heads as shown in Fig. 13. These rollers are accommodated in the elongated openings 31 and 32 in the front wall 21 of the trough structure and in the elongated openings 36 and 37 in the rear wall 22. The rollers 88 extend through the loops 48 and 49 on the carrier member. The horizontal elongation of the openings in the walls of the trough structure provide for lateral movements of the carrier member as disclosed in my copending application Serial No. 389,655, filed November 2, 1953.

During lateral movements of the carrier member with respect to the striker it is supported on the rollers 82 which roll on the spring abutment member. The downwardly facing concave surfaces 63 and 64 on the carrier member and the upwardly facing concave surfaces 71 and 72 on the spring abutment member 67 serve to return the carrier member to a central position within the striker opening 17 to thereby provide swing hanger action for the carrier member.

During lateral movements of the carrier member the spring abutment member 67 is restrained from moving horizontally. The rib 77 which extends into the slot or space 76 between the ears 73 and 74 and the lug 79 which extends into the groove 81 prevent the abutment member 67 from partaking of the lateral movements of the carrier member. The spring abutment member is free to move vertically as the springs 66 are compressed and during expansion of these springs. In all vertical positions of the abutment member 67 it is restrained from moving laterally with respect to the striker because of the interlocking arrangement of the ears 73 and 74 with the rib 77 and the lug 79 with the groove 81. Accordingly the upper end portions of the supporting springs 66 are not shifted laterally during horizontal angling of the coupler stem and there are no shearing stresses developed in the supporting springs 66.

In mounting the carrier on the striker the springs 66 are first arranged within the trough structure with their lower ends surrounding the spring positioning lugs 26. The spring abutment member 67 is then arranged over the upper ends of the springs. The rollers 82 are applied to the concave surfaces 71 and 72. The carrier member is then arranged in an angular position so that one of the loops may be moved through an open area 24. Thereafter the carrier member is swung to a horizontal position so that the concave surfaces 63 and 64 rest on the rollers 82. The carrier member is moved downwardly to compress the springs and the rollers 88 are introduced through the openings 31 and 32 in the front wall and through the loops 48 and 49. The enlarged heads of the rollers are then applied to the shaft portions of the rollers adjacent the openings 36 and 37. The rollers 88 limit upward movement of the carrier member which is then in condition for operation.

The carrier assembly has particular utility for an interlocking type coupler but it may also serve to support the draw bar of other types of couplers. Various changes may be made in the structure of the separate parts and such modifications along with changes in the general organization may be made without departing from the spirit and scope of the invention as set forth in the appended claims.

65 What I claim and desire to secure by Letters Patent is:
 1. In a carrier assembly for the draw bar of a railway coupler, a striker having an opening in the front thereof for accommodating the draw bar, a trough structure at a forward portion of the striker below said opening, an abutment member adjacent an upper portion of said trough structure, springs within the trough structure resiliently supporting said abutment member, a vertically extending rib carried by and within said trough structure, said abutment member having a slot therein receiving said rib preventing lateral motion of the abutting mem-

ber, a carrier member under said draw bar and overlying said abutment member, a downward facing concave surface on the carrier member, an upward facing concave surface on the abutment member, a roller in rolling engagement with the concave surface of the abutment member and in rolling engagement with the concave surface of the carrier member, and means limiting upward movement of the carrier member with respect to the striker.

2. In a carrier assembly for a railway coupler, a striker having an opening in the front thereof for accommodating a coupler stem, a trough structure including a front wall carried by a forward portion of the striker below said opening, an abutment member adjacent an upper portion of said trough structure, springs within the trough structure resiliently supporting said abutment member, a vertically extending rib within and carried by the front wall of said trough structure, said abutment member having a slot therein receiving said rib preventing lateral movements of the abutment member, a carrier member under said stem and overlying said abutment member, downward facing concave surfaces on the carrier member, an upward facing concave surface on the abutment member under each downward facing concave surface providing pairs of confronting arcuate surface, a roller between each pair of arcuate surfaces, and means limiting upward movement of the carrier member with respect to the striker.

3. In a support for a railway coupler, a striker, a trough structure carried by a lower forward portion of the striker having generally vertical front and rear walls, an abutment member adjacent an upper end of said trough structure, springs within the trough structure supporting said abutment member, a vertically extending rib carried by said front wall within the trough structure, said rear wall having a vertically extending groove therein, a lug carried by a rear portion of the abutment member extending within said groove, said abutment member having a slot in the front portion receiving said rib, a carrier member overlying said abutment member, downward facing concave surfaces on the carrier member, upward facing concave surfaces on the abutment member, a roller in rolling engagement with one of the concave surfaces of the abutment member and in rolling engagement with one of the concave surfaces of the carrier member, another roller in rolling engagement with another of the concave surfaces of the abutment member and in rolling engagement with another of the concave surfaces of the carrier member, and means limiting upward movement of the carrier member with respect to the striker.

4. In a draft rigging for a railway coupler, a striker having an opening in a front portion thereof, a trough structure carried by a lower forward portion of the striker having generally vertical front and rear walls, a vertically extending rib carried by the front wall within the trough structure, and said rear wall of the trough structure having a vertically extending groove therein.

5. A spring abutment member for a carrier assembly for a railway coupler, a plate having a substantially flat under face, spring positioning lugs projecting from said face, upward facing concave surfaces on the upper portion of said plate, a pair of ears depending from an intermediate portion of said plate having a vertically

disposed space between adjacent edges thereof, and a lug depending from an intermediate rear portion of said plate.

6. A carrier assembly for a railway coupler comprising, a striker, a trough structure carried by a lower forward portion of the striker having a bottom wall, said striker having a front opening above the trough structure for accommodating a coupler stem for lateral movements with respect to the striker, a carrier member having a top plate for engaging an under surface of the coupler stem overlying said trough structure and adapted to move laterally with respect to the striker with such movements of the coupler stem, helical vertically disposed springs within the trough structure with lower ends thereof engaging said bottom wall, a spring abutment member engaging upper ends of said springs resiliently supported on said springs for vertical movements relative to the striker, rollers between the spring abutment member and the carrier member supporting the carrier member on the spring abutment member and during said lateral movements of the carrier member, means limiting upward movement of the carrier member relative to the striker, and vertically disposed guide means adjacent an intermediate portion of the trough structure preventing lateral movements of the spring abutment member relative to the striker throughout the range of vertical movements thereof whereby lateral movements of upper portions of said springs relative to lower portions thereof are avoided during lateral movements of the carrier member relative to the striker.

7. A carrier assembly for a railway coupler comprising, a striker, a trough structure carried by a lower forward portion of the striker, said striker having a front opening above the trough structure for accommodating a coupler stem for lateral movements with respect to the striker, an abutment member, vertically disposed helical springs resiliently supporting said abutment member on the trough structure for vertical movements with respect to the striker, a carrier member engaging an under surface of the coupler stem adapted to move laterally with respect to the striker during such movements of the coupler stem, rollers supporting the carrier member on the abutment member and rolling therebetween during said lateral movements of the carrier member relative to the striker, means limiting upward movement of the carrier member relative to the striker, vertically disposed inter-engaging guide surfaces carried by intermediate portions of the abutment member and the trough structure preventing lateral movements of the abutment member relative to the striker throughout the range of vertical movements thereof whereby upper portions of the springs remain substantially in alignment with lower portions during lateral movements of the carrier member relative to the striker.
